(57) **CLAIM**

The ornamental design for a carpenters' clamp as shown and described.

DESCRIPTION

FIG. 1 is a top, front and left side perspective view of a carpenters' clamp showing the new design;

FIG. 2 is a further perspective view thereof;

FIG. 3 is a left side elevational view thereof;

FIG. 4 is a top plan view thereof;

FIG. 5 is a right side elevational thereof;

FIG. 6 is a bottom plan view thereof; and

FIG. 7 is a rear elevational view thereof; and,

FIG. 8 is a front elevational view thereof.

The broken line showing of various elements in FIGS. 1, 2, 4, 7 and 8 forms no part of the claimed design.

1 Claim, 7 Drawing Sheets
